UNITED STATES PATENT OFFICE.

LYMAN F. MCNETT, OF YONKERS, NEW YORK, ASSIGNOR TO THE AMERICAN MOTOR COMPANY, OF NEW YORK, N. Y.

COMBINED GAS-ENGINE AND CARBURETOR.

SPECIFICATION forming part of Letters Patent No. 407,961, dated July 30, 1889.

Application filed September 15, 1887. Serial No. 249,800. (No model.)

To all whom it may concern:

Be it known that I, LYMAN F. MCNETT, a citizen of the United States, and a resident of the city of Yonkers, county of Westchester, 5 and State of New York, have invented a new and useful Improvement in Combined Gas-Engine and Carburetor, of which the following description, in connection with the accompanying drawings, is a specification, like 10 letters on the drawings representing like parts.

My invention relates to an organization of apparatus in which water is circulated in such manner as to keep the cylinder of a gas-engine cool, and to heat a gas-generator for carbureting air with naphtha or other volatile hydrocarbon to make gas.

My invention consists in the combination of apparatus hereinafter described, and comprising exhaust and inlet pipes properly arranged 20 between a jacket for the gas-engine and a jacket or reservoir for a gas-generator by which air may be carbureted with naphtha or other volatile hydrocarbon, as will be hereinafter more fully described.

25 The cylinder of a gas-engine must be kept cool while in operation, which is ordinarily done by allowing cold water to pass through a chamber or jacket which surrounds the cylinder of the engine, the water being supplied 30 by a pump or tank. By this system a large amount of water is wasted. To save this expense and avoid the carrying of a large amount on cars which are propelled by gas-engines, I use the water over and over again, 35 utilizing the heat of the water as it comes from the chamber or jacket of the engine to generate naphtha or other hydrocarbon gas in a generator provided with a water-jacket, which generator in turn cools the water and 40 causes it to be returned to the chamber or jacket of the engine, on the principle of the difference in density or gravity of hot and cold water.

In the accompanying drawings, Figure 1 45 shows apparatus embodying my invention, the gas-engine being shown in side elevation and the carburetor and appliances used therewith in longitudinal section. Fig. 2 is a cross-section on the line XX of Fig. 1. Fig. 3 is a cross-section on the line YY.

A generator D, of the kind hereinafter described or of any other suitable character, is wholly or partially surrounded by a jacket K, as shown, being formed of outer and inner walls A R with ends a. The outer wall or shell A is provided with double heads, forming spaces L L, which serve as a protection for the various appliances used in the construction. This reservoir or jacket K receives the heated water through the pipe B as it 60 comes from the jacket or chamber H, surrounding the cylinder G of the gas-engine.

The generator D consists of a cylinder mounted on a hollow perforated shaft V, which is provided with a pulley m, by which the cylinder may be rotated. The cylinder D rotates in a chamber O, containing a volatile hydrocarbon, and is provided with a series of floats d, made as absorbents and consisting of woven wire or cloth filled with some absorbent material and attached to the inside of the cylinder D. The cylinder D is made of open-work— 70 as, for instance, of woven wire or of a sheet of perforated material like iron. The floats d take up the naphtha in the chamber O and 75 distribute it or allow it to fall in fine streams or as drops in the upper part of the cylinder.

J is an inlet which permits the air to be forced into the carburetor through the hollow 80 shaft, and N an outlet through which the carbureted air is carried away for use.

The pipe B is the exhaust for the heated water to pass out of the chamber H of the engine and connects with the reservoir K, as 85 shown in Fig. 1. By this means the hot water is allowed to drip over the shell of the generator and heats the naphtha more readily, and then as it becomes cold settles and passes out by the exhaust-pipe C into the 90 chamber H at L. Thus a circulation is kept up between the engine E and the reservoir or jacket K, the explosion of the gas in the cylinder G heating the water in the chamber or jacket H and causing it to pass through the 95 pipe B to the jacket, where it becomes cold by heating the naphtha and forming gas when it is returned to the jacket H again.

My invention is designed especially for application to gas-engines which are used to pro- 10

pel cars or vessels, and are supplied with gas manufactured on the car or vessel as often as it is needed. I do not, however, limit myself to this special application of the invention.

5. What I claim as my invention is—

The combination, substantially as described, of a gas-generator, a jacket therefor, a gas-engine having a cooling-jacket, and circulating-pipes, as described, for circulating a heating-
10 and cooling fluid through the jacket of the engine and the jacket of the generator.

In testimony that I claim the foregoing as my invention I have signed my name, in presence of two witnesses, this 15th day of February, 1887.

LYMAN F. MCNETT.

Witnesses:

AUGUSTUS MERRITT,
ALBERT HENSEL.
